UNITED STATES PATENT OFFICE.

CHARLES REMELIUS, OF NEWARK, NEW JERSEY, ASSIGNOR TO COLUMBIA
MACHINE WORKS AND MALLEABLE IRON COMPANY, OF BROOKLYN,
NEW YORK, A CORPORATION OF NEW YORK.

FUSE-BOX.

No. 851,560.

Specification of Letters Patent. Patented April 23, 1907.

Application filed February 6, 1907. Serial No. 356,002.

To all whom it may concern:

Be it known that I, CHARLES REMELIUS, a citizen of the United States, residing at Newark, in the county of Essex and State of New Jersey, have invented an Improvement in Fuse-Boxes, of which the following is a specification.

This invention relates to a fuse box or protective device for apparatus employed in electric circuits and relates particularly to that class of fuse boxes which are positive in action,—that is, in which the fuse device cannot attain and remain in a molten hanging condition before being ruptured by an excess current.

In carrying out my invention, I preferably employ a casing, terminal connections therein, a fuse device, means electrically connected to the said terminal connections and normally held in an operative position by the said fuse device and means operative upon the passage of an excess current for throwing the aforesaid means into an inoperative position and thereby opening the circuit, as will be hereinafter more particularly described.

In the drawing, Figure 1 is an elevation of my improved fuse box, showing the same with the cover open. Fig. 2 is an elevation of the fuse box with the cover closed. Fig. 3 is a section on line *x*, *x*, Fig. 2, and Fig. 4 is a section on line *y*, *y*, Fig. 2.

Referring to the drawing, *a* designates a casing which is preferably made rectangular in cross section and of asbestos, vulcabeston or any other suitable insulating material or compounds of insulating materials. The casing *a* on one side thereof is provided with a cover *b* which is shown as connected to the casing by means of the hinges 10. This cover *b* may be provided with a knob 11, and the top of the casing with the spring catch 12, by means of which the door or cover is normally secured in position.

Within the casing *a* I employ a partition *c* made of fiber or any other insulating material and extending from the bottom of the casing to a point appreciably distant from the top member thereof. This partition *c* substantially divides the interior of the casing into two equal compartments and in each of these compartments and in similar positions therein, I employ a binding post or terminal connection *d* which is adapted to re-

ceive and be connected to the lead wires 13 by means of the set screws 14 or otherwise. In each compartment within the casing, I also employ a block *e* secured thereto in any desired manner and electrically connected with the terminal *d* by means of an arm 15 or otherwise, and the block *e* is provided with an axle 16 upon which is mounted a swing arm *f*.

h represents a spring, one end of which is adapted to engage the inner edge of the swing arm *f*, the spring being passed around the axle 16 and the other end secured to a pin 17 also fixed in or integral with the block *e* and the swing arm *f* and the spring *h* are secured in position on the said axle 16 by means of a washer 18 passed over the end of the axle and the pin 19 passing diametrically through the same.

Normally the swing arms *f* are secured in an operative position,—shown in full lines in Fig. 1,—by means of the fuse wire *i* of any suitable material being passed around their outer ends and across the top of the partition *c*.

k, *k*, are stop blocks, one of which as shown, is fixed in each of the compartments within the fuse box and also in each of these compartments I prefer to employ a deflector 20 placed substantially in the position shown and adjacent to which the ends of the fuse box are provided with the openings 21.

As will be apparent in the operation of the hereinbefore described fuse box, the current will pass by the way of one lead wire into one of the compartments within the box, through the terminal *d* therein, arm 15 to the block *e* thence through the swing arm *f* and by way of the fuse wire *i* to the similar parts in the other compartment and of course through the same in the opposite or reverse order. Now by means of the springs *h*, the fuse wire *i* in maintaining the swing arms in the normal position as shown in Fig. 1, is under considerable tension and upon the passage of an excess current and upon the slightest weakening of the fuse wire, the swing arms *f* will part destroying the continuity of the fuse and assume the positions shown in dotted lines Fig. 1, stopping against the stop-blocks *k*. In so doing, the arc generated will raise the temperature within the fuse box, thereby increasing the pressure which forces

the arc to become dissipated, being deflected around the deflectors 20 and through the openings 21 in the ends of the box.

I claim as my invention:

- 5 1. A fuse box comprising a casing having an opening in the end thereof, a terminal connection within the said casing, a swing arm pivotally mounted within the said casing, electrical connection between the said swing arm and said terminal connection, a fuse device by which the said swing arm is normally maintained in an operative position, means operative upon the passage of an excess current for throwing the said swing arm into an inoperative position, a deflector of insulating material set at an angle and extending interiorly across the said box adjacent to said opening in the end thereof.
- 15 2. A fuse box comprising a casing having an opening in each end thereof, a partition

dividing the said casing interiorly into two compartments, a terminal connection in each of the said compartments, a swing arm electrically connected to each of the said terminal connections, a fuse device for normally 25 maintaining the said swing arms in operative positions, means operative upon the passage of an excess current for throwing said swing arms into inoperative positions, deflectors, one of which is placed at an angle 30 in each of the said compartments within the box and adjacent to said opening in the adjacent end thereof.

Signed by me this 30th day of January, 1907.

CHARLES REMELIUS.
